UNITED STATES PATENT OFFICE.

THOMAS F. BYRON, OF CHICAGO, ILLINOIS, ASSIGNOR OF ONE-HALF TO WILLIAM B. LEDDY,
OF CHICAGO, ILLINOIS.

DRAPERY-FIXTURE.

No. 860,963.

Specification of Letters Patent.

Patented July 23, 1907.

Application filed July 10, 1905. Serial No. 268,950.

To all whom it may concern:

Be it known that I, THOMAS F. BYRON, a citizen of the United States, residing at Chicago, in the county of Cook and State of Illinois, have invented a new and useful Drapery-Fixture, of which the following is a specification.

My invention relates particularly to drapery fixtures adapted for use in connection with dressers, and the like; and my primary object is to provide cheap and simple fixtures which may be readily employed without injury to the chamber walls.

My invention is illustrated in its preferred embodiment in the accompanying drawing, in which—

Figure 1 is a broken perspective view of a dresser and drapery fixtures designed for use in connection therewith; Fig. 2, a perspective view of one portion of the hanger shown in Fig. 1, in reversed position; and Fig. 3, a broken rear perspective view of the dresser and one of the bracket arms connected therewith.

20 In the drawing, A represents a dresser equipped with standards A¹ supporting a mirror A²; B, a pair of bracket arms connected with the standards A¹; B¹, a hanger having an adjustable bracket-arm B²; and B³, drapery, or a throw, supported by the bracket-arms B, B².

25 Each bracket-arm B comprises a forwardly projecting arm b terminating in an ornamental end b¹, and an in-turned end b² forming substantially a right-angle with the arm b. Each arm b² is provided with a series of screw-receiving perforations b³, and each arm is connected with a standard A¹ by screws b⁴. Each arm b² is provided with nicks, or cuts, b⁵, enabling the arm to be broken off so as not to interfere with the mirror when

the bracket-arms B are adjusted to lessen the distance between them.

The hanger comprises preferably a bar b⁶ equipped 35 at its upper end with a hook b⁷ and provided with a plurality of perforations b⁸; and the bracket B² having a horizontal member b⁹ and a brace member b¹⁰. The member b⁹ has an ornamental front end b¹¹ and is equipped at its rear end with a loop b¹² slidable upon 40 the vertical member b⁶. The brace member b¹⁰ has a vertical portion b¹³ at its lower inner end which is adapted to bear against the vertical member b⁶ and which is equipped with a stud b¹⁴ adapted to enter any desired one of the perforations b⁸. Thus, ready adjustment of the bracket B² is provided for. In the illustration shown, the hook b⁷ is shown in engagement with the molding C of a chamber wall. However, the member b⁶ may be supported on a hook, or it may be secured at its lower end by means of screws to the upper 50 portion of the mirror frame.

It will be observed that different effects in the drapery may be secured by adjusting the brackets B and the bracket B² with relation to each other.

What I regard as new, and desire to secure by Letters Patent, is—

A hanger for the purpose set forth, comprising a vertical member provided at its upper end with a molding hook and having a plurality of perforations, and a bracket comprising a horizontal member slidably connected with said vertical member and a brace-member having a pin adapted to enter any desired perforation.

THOMAS F. BYRON.
